BARBECUE GRILL OR SIMILAR ARTICLE

Robert L. Spillman, Canal Winchester, Ohio, assignor to William Coons, Columbus, Ohio

Application December 30, 1957, Serial No. 49,062

Term of patent 7 years

(Cl. D81—10)

Figure 1 is a perspective view of a barbecue grill or similar article showing my new design;

The side and end of the barbecue grill or similar article, not shown in the drawing, are identical to the side and end as shown in Figures 2 and 3.

I claim:

The ornamental design for a barbecue grill or similar article, substantially as shown and described.
